UNITED STATES PATENT OFFICE.

SAMUEL F. NEWMAN AND JAMES G. HARPER, OF WAYNESBORO, PENNSYLVANIA, AS
SIGNORS TO LANDIS MACHINE COMPANY, OF WAYNESBORO, PENNSYLVANIA, A
CORPORATION OF PENNSYLVANIA.

DIE HEAD.

Application filed August 7, 1922. Serial No. 580,210.

Our said invention relates to certain improvements in a die head for cutting threads on bolts and pipes and for similar purposes, the general features of the device being similar to what is shown in the patent to Miller 1,296,546, March 4, 1919.

It is an object of our invention to provide such a die head with improved adjusting means and with means for protecting the parts against the intrusion of metal shavings and other foreign matter.

Another object of our invention is to provide an improved arrangement of parts for adjusting the cutters in case a rough cut and a second or finishing cut should be desired. Still another feature consists in improved connecting devices between the parts of the head for holding the same in closed position.

Referring to the accompanying drawings which are made a part hereof and on which similar reference characters indicate similar parts,

Figure 1 is a front view of our device,

Figure 2, a rear view thereof,

Figure 3 a section on line 3—3 of Figure 1,
Figure 4, a similar section on line 4—4 of

Figure 1,

Figure 5, a section on line 5—5 of Figure 1,

Figures 6, 7, 8 and 9 details showing the position of parts for certain cutting operations, and

Figures 10 and 11 details showing modified connecting pins.

In the drawings 10 indicates the shank by which the die head is held in the machine, the shank having a forwardly projecting flange 11 constituting a ring frame or ring casing rigid with the shank. A pair of rings 12 and 13 are attached to said flange, the ring 12 being held to the flange 11 by a longitudinally yieldable connection including bolts 12' as in Figure 4 of the patent above referred to. The body 14 of the die head is located concentrically with the flange 11 and rings 12 and 13 and is held in place by the ring 12 through the medium of screws 12', the springs surrounding them, and shoulder 16 of the head body which is spaced from the ring 12 by the thin ring 15. Ring 13 turns on the body for opening and closing the head by means of pin and slot connections between the ring and the head as indicated at 26 (Fig. 1). A ring 18 has a driving fit on a reduced annular part of body 14, and fits closely in an annular recess

in ring 13, thereby serving to hold the parts in place and also to close the joint between the body and the ring. Thus it will be seen that head body 14, ring 18, rings 13, 12 and 15 form a unit which moves forward away from flange 11 in opening the head, as hereinafter explained. The ring 15 also has a flange 17 extending rearwardly over the flange 11 to protect the joint between parts 11 and 15 against the entrance of dirt, when the body of the head moves away from flange 11 and flange 17 has zero marks adapted to register with the marks of a scale on the flange 11 to indicate different rotary positions of adjustment of the body relative to the shank. The ring 15 is fixed to the body by a spline 15' to rotate therewith and has elongated slots 15'' for screws 12', 34 and 35 to permit movement of the ring relative to flange 11 and ring 12. The body is held in place at the front by a ring 18 engaging grooves in its face and in the face of the ring 13, this ring being held in place by screws 19 (Fig. 9) engaging holes in the body.

Trunnions 21 are located in openings of the body, these trunnions being internally threaded and having extensions 22 on which are mounted jaws in the form of cutter holding blocks 23 carrying longitudinally-grooved chasers 23' for forming screw threads, pipe threads, etc. The chasers here shown are of the well-known Landis type, and are held in blocks so arranged as to act tangentially of the work in all positions of adjustment. The blocks are held in place by screws 24, the trunnions being held in the bores of the body by screws 25 all as in Patent No. 1,296,546, above referred to. Pin and slot connections are also provided at 26 as in said patent by means of which the position of the chasers may be adjustably determined. In Figure 5 there is shown an adjusting device carried by the ring 12. This adjusting device comprises a shaft in the form of a bolt 27 having a worm 28 formed thereon and adapted to engage worm teeth at 29 on the body 14. The head of the bolt is graduated, as shown at 30, a zero mark 90 being formed on the bore adjacent thereto. A nut 31 having notches or recesses at 31' for engagement by a spanner and a lock nut 32 of ordinary type are provided for securing the adjusting bolt under proper tension so that it is always in operative relation and needs no locking to hold the parts in adjusted position, nor unlocking to permit adjustment of the

head for size; in other words by this construction I am able to adjust the nut 31 on the shaft 27 and lock it in place in such a manner that the shaft and the worm will turn with sufficient freedom for purposes of adjustment yet without any end play. Such end play is undesirable in that it causes inaccuracy in the adjustment and therefore in the operation of the head but none of the devices hitherto in 10 use for securing this adjustment has been free from this objection so far as known to us.

Spring 33 are provided in the body and engage the cutter holding blocks to open the die by rotating the ring 13 about the 15 body 14 as in the prior patent and such rotation is normally prevented by pins 34 and 35 passing through members 12 and 15, ring 15 having clearance openings 15" to permit rotary movement of body 14 and ring 15 relative to flange 11 and ring 12. The pin 34 is secured to shank 10 in any convenient manner and extends through rings 15 and 12, having at its forward end an extension 36 engaging in a hardened bushing 37 on 20 ring 13. It will be noted that the pins 34 and 35 have blunt ends, in contradistinction to the tapered ends of the locking pins in such heads as that shown in the patent to Landis 948,893.

30 A second internally-threaded bushing or nut 38 is located below bushing 37. When the bushings are to be removed or replaced a threaded rod is engaged with bushing 38, and both bushings are removed by a pull on 35 the rod. This arrangement renders it easy to remove and replace bushings 37 which are subject to considerable wear. The bushings, as will be evident, may be turned end for end in the interest of economy. Pin 35 has a 40 flange at 40, which may be omitted if preferred, by which the pin is held in position on flange 11, said pin extending also through ring 12 and having an extension 39 engaging a bushing 37 as in the case of extension 36 of 45 pin 34. By reference to Figures 6 to 9 it will be seen that the extension 39 has a reduced eccentric face at the righthand side while the extension 36 has a reduced eccentric face at each side for a purpose which 50 will presently appear. These eccentric faces are formed on arcs of circles corresponding to the circle of the hole in the cooperating bushing 17. Thus the sides of the pins are caused to fit against the inner sides of the 55 bushings without line contact.

The pin 35 at its rear end has a handle 41 secured thereto by a pin 42, by means of which it may be rotated through a semi-circumference, the movement of the handle being limited by pins 43. An internal bushing 44 bridges the space between the shank 10 and the body 14 and prevents chips and other foreign matter from gaining access to the interior of the die head through the central passage.

In the operation of our device the cutter heads are arranged as shown in Figure 1 and adjusted by the means shown in Figure 5, the extent of such adjustment being indicated by the position of the zero mark on flange 17 relative to the scale on flange 11. The ring 13 is then moved by a handle 45 thereon to position the parts as shown in Figure 3 for operation whereupon pins 34 and 35 engage in bushings 37 due to the force 70 of springs 50 (Fig. 2) surrounding bolts 12'. If a single right-hand cut is desired the lever 41 is positioned as shown in Figure 9 with the eccentric face of extension 39 to the left to receive the pressure of tools and operating devices and transmit the strain to the shank 10. If a second or finishing cut is desired the lever is turned over to locate the eccentric face on the extension on the opposite side, whereby the ring 13 is forced 80 into a position to adjust the cutters closer in and thus produce the finishing cut. In the first position it will be seen that the extension 36 of pin 34 takes part in the work but in the second position as shown in Figure 8 it does not bear any of the pressure or thrust.

If a left-hand cut is desired the cutter heads (or the cutter heads and trunnions as the case may be) are removed and replaced by left-hand cutter heads, the relative location of trunnion bearings and springs 33 being such as to permit ready substitution of cutter heads. The handle 41 is then positioned as shown in Figure 7 if but one cut 95 is desired, whereas if a second cut is to be made the handle is thrown over as shown in Figure 6. In this case as when cutting to the righthand the extension 36 takes part in the first cut but not in the second.

As is common in machines of this type the rings 12 and 13 and the body 14 are adapted for forward movement relatively to the shank when an operation of cutting a thread on a screw or pipe has proceeded sufficiently far. This results in withdrawing extensions 36 and 39 from the bushing 37 whereupon the heavy pressure of the springs 33 combined with the outward pressure between the work and the cutters causes the cutters to move outward and the ring 13 to revolve whereby a relative movement of rotation is given to the extensions 36, 39 and bushing 37. In this rotating movement it will be seen that the extensions 36, 39 maintain facial contact with the ends of the bushings 37 so that the principal wear takes place on the ends of the renewable hardened bushings instead of on the ring 13. The rotary movement of ring 13 is limited by one or more pins 46 on ring 12 projecting into openings 47 of ring 13.

The pins 34 and 35 serve as locking pins to hold the closing ring securely in head-closing position while they also serve as driving pins 130

to transmit the drive of the shank 10 to the head body in the case of a rotary head or to prevent rotation of the head body in the case of a non-rotary head. The provision of a plurality of driving pins eliminates all tendency for one or more parts of the head to rotate about a driving pin, as frequently occurs where a single driving pin is used for locking the head, and provides a very strong and secure drive. We do not limit ourselves to such pins having eccentric faces but may utilize a pin with a concentric extension as shown at 48 or a straight pin 49 if preferred.

The device above described is particularly well adapted for use as a stationary automatic die head, and in the larger sizes of such heads though not limited to use in any particular type or size of machine. It will be obvious to those skilled in the art that many other changes may be made in the device above disclosed without departing from the spirit of the invention, the true scope of which is indicated in the appended claims.

Having thus fully described our said invention, what we claim as new and desire to secure by Letters Patent, is:

1. A die head comprising a shank, a ring frame rigid therewith, a body within the ring frame, cutters carried by said body and connected to said ring frame and means for adjusting said cutters comprising worm teeth on the body, a shaft on the ring frame tangential to the body, a worm on the shaft engaging said teeth, means to prevent end play of the shaft including a head at one end of the shaft bearing against a face on the ring frame, a nut at the other end of the shaft bearing against another face on the ring frame, and means to lock said nut against rotation, substantially as set forth.

2. A die head comprising a body, radially movable tangential chasers on said body, a ring rotatable relatively to said shank and body and connected to said chasers for opening and closing the die head, resilient means acting on the ring to open the head, a handle on the ring for moving the same to close the head, and means for maintaining said chasers in closed position comprising one or more pins on one of the relatively rotatable members of said die head and fixed abutments on another of said members against which said pins may rest, said pins being movable lengthwise of the head and out of engagement with said last-named member, substantially as set forth.

3. A die head comprising a body, radially adjustable tangential chasers on said body, a ring rotatable relatively to said body and connected to said chasers for opening and closing the head and means for maintaining said chasers in closed position comprising openings in one of the relatively rotatable members of said die head, one or more pins on another of said members approximately

equal in size to said openings said pins being wholly withdrawn to permit said head to open, and bushings in said openings adapted to engage the periphery of said pins, substantially as set forth. 70

4. A die head comprising a body, radially adjustable tangential chasers on said body, a ring rotatable relatively to said shank and body and connected to said chasers for opening and closing the head and means for maintaining said chasers in closed position comprising one or more pins on one of the relatively rotatable members of said die head, openings on another of said members for receiving said pins, and bushings in said openings adapted to surround said pins, the relative rotation between such parts being such that the ends of said pins do not move beyond the periphery of said bushings, substantially as set forth. 75

5. A die head comprising a body, radially adjustable tangential chasers on said body, a ring rotatable relatively to said shank and body and connected to said chasers for opening and closing the head and means for maintaining said chasers in closed position comprising a pin on one of the relatively rotatable members, an opening in the other, a bushing in the opening surrounding said pin, and a threaded nut beneath the bushing and at the bottom of the opening, substantially as set forth. 80

6. A die head comprising a body, radially adjustable tangential cutters on said body, a ring rotatable relatively to said body and connected to said cutters for opening and closing the head, and means for maintaining said cutters in closed position comprising a pin on one of said members, and an opening in the other to receive the end of the pin, said pin having an eccentrically reduced portion 95 at one end extending into said opening, substantially as set forth. 100

7. A die head comprising a body, radially adjustable tangential cutters on said body, a ring rotatable relatively to said shank and body and connected to said cutters for opening and closing the head, and means for maintaining said cutters in closed position comprising a pin on one of said members and an opening in the other to receive the end of the pin said pin having eccentrically reduced portions at opposite sides extending into said opening, substantially as set forth. 110

8. A die head comprising a body, radially adjustable tangential cutters on said body, a ring rotatable relatively to said body and connected to said cutters for opening and closing the head, and means for maintaining said cutters in closed position comprising diametrically opposite pins on one of the relatively rotatable members of said die head and openings on another of said members for receiving said pins, one of said pins having an eccentrically reduced portion at one side and the other having eccentrically reduced por- 115 120 125 130

tions at both sides, substantially as set forth.

9. A die head comprising a body, radially adjustable tangential cutters on said body, a ring rotatable relatively to said body and connected to said cutters for opening and closing the head, and means for maintaining said jaws in closed position comprising a pin on one of said members, an opening in the other to receive the end of the pin, said pin having an eccentrically reduced portion at one end extending into the opening, and means for imparting to said pin movements of partial rotation whereby said cutters may produce a rough cut and a finishing cut, substantially as set forth. 75

10. A die head comprising a shank, a body rigid therewith, radially adjustable longitudinally grooved tangential cutters on said body, a ring rotatable relatively to said shank and body and connected to said cutters for opening and closing the head, and means for maintaining said jaws in closed position comprising one or more pins on one of the relatively rotatable members of said die head and openings on another of said members for receiving said pins, one of said pins having an eccentrically reduced portion at one side and the other having eccentrically reduced portions at both sides, and means for imparting to said first-named pin movements of partial rotation whereby said cutters may produce a rough cut and a finishing cut, substantially as set forth. 80

11. A die head having means for supporting right-hand or left-hand cutters interchangeably, means for radial adjustment of said cutters and common means for varying the position of said cutters to produce a first cut and a deeper second cut in either direction of rotation comprising a ring connected to said cutters for opening and closing them, one or more pins for holding the ring in closed position, and means for temporarily varying the position of said ring to change the adjustment of the cutters, substantially as set forth. 95

12. A die head having means for supporting right-hand or left-hand cutters interchangeably, means for radial adjustment of said cutters and common means for varying the position of said cutters to produce a first cut and a deeper second cut in either direction of rotation comprising a ring connected to said cutters for opening and closing them, said ring having an opening and a pin on the head having an eccentric extension in said opening whereby the position of the cutter may be temporarily changed to a predetermined extent, substantially as set forth. 100

13. In a die head, a shank having a flange, a ring located forwardly thereof, a body within the ring adjustable in a rotary sense relatively to the shank and movable longitudinally with the ring relatively to the shank, said body having an annular shoulder near its

rear end, a thin ring splined to the body and confined between said shoulder and said first-named ring, said latter ring having elongated openings, pins passing through said openings and fitting in holes in the flange and first-named ring, headed pins extending through said flange and said thin ring and threaded into said first-named ring, and springs bearing against said heads to hold the parts in contacting relation, substantially as set forth. 75

14. A cutter head having cutters to form screw-threads, means for opening and closing the head including a rotary member, and one or more axially extending pins to engage the rotary member for locking it in closed position, said pins being wholly withdrawn from said member for permitting the head to open, and hardened renewable parts on said rotary member for engagement by said pins, substantially as set forth. 80

15. A cutter head having cutters to form screw-threads, rotary means for opening and closing the head, one or more axially extending pins to engage the rotary member for locking it in closed position, and one or more of said pins having eccentric lateral faces whereby the depth of cut may be varied, substantially as set forth. 90

16. A cutter head having cutters to form screw-threads, rotary means for opening and closing the head, one or more axially extending pins to engage openings in the rotary member for locking it in closed position, and one or more of said pins having eccentric lateral faces whereby the depth of cut may be varied, said faces being struck on the same radius as the circumference of the openings to prevent a line contact between a pin and the sides of an opening, substantially as set forth. 100

17. A cutter head having cutters to form screw-threads, rotary means for opening and closing the head, one or more axially extending pins to engage openings in the rotary member for locking it in closed position, bushings in said openings, one or more of said pins having eccentric lateral faces to engage the sides of said bushings and said faces corresponding to the internal periphery of the bushing to prevent line contact therewith, substantially as set forth. 110

18. A die head comprising a body, trunnions extending lengthwise of the body and rotatable relatively thereto, blocks on the trunnions, chasers fixed to the blocks, a ring rotatable on the body to open and close the head and having eccentric lost-motion connection with said blocks, and means extending lengthwise of the body and engaging the ring to lock the head in closed position, substantially as set forth. 120

19. A die head comprising a body, a shank carrying the body, cutter-supporting trunnions on the body, a ring rotatable on the body and connected to the trunnions for opening and closing the head, and one or more

- self-locking pins fixed to move with the shank and adapted to engage directly with said ring said pins being wholly disengaged from said ring by axial movement of the ring and the body relatively to the shank, substantially as set forth.
20. In a die head, a shank, a body supported thereby, an annular series of tangential chasers on the body, a ring rotatable on the body and connected to the chasers to open and close the head, means for moving the ring yieldingly in one direction, and means to hold the head closed comprising one or more pins on the flange adapted to engage circular openings in the head said pins having arcuate reduced areas at their ends corresponding to the sides of said circular openings, substantially as set forth.
21. In a die head, a shank, a body carried by the shank and movable axially relatively thereto, an annular series of chasers on the head, a ring rotatable on the head to open or close the same, and pins on the shank adapted to engage circular openings on the head said pins having flattened faces adapted to rest against the sides of said circular openings without line contact, substantially as set forth.
22. In a cutter head, a body having means for supporting either a set of right-hand or a set of left-hand cutters, a handle on the head mounted to move in a plane intersecting the axis of the head, and connections from the handle to the cutter-supporting means whereby the depth of cut of either set may be predetermined by oscillatory movements of the handle in said plane, substantially as set forth.
23. In a cutter head, a body having means for supporting either a set of right-hand or a set of left-hand cutters, a ring surrounding the body said ring being connected to the cutter-supporting means, a handle for moving the ring to open and close the head, a pin movable axially with respect to the head said pin adapted to engage the ring to lock the head in closed position, and means for adjusting the pin with reference to the remainder of the die head to vary the working position of the cutters, substantially as set forth.
24. A cutter head having cutters to form screw-threads, means for opening and closing the head including a rotary member, an axially extending pin adapted to engage the rotary member for locking it in closed position, and means for rotating said pin about its axis to vary the depth of cut, substantially as set forth.
25. A die head having means for supporting right-hand or left-hand cutters interchangeably, common means for varying the position of said cutters to produce a first cut and a deeper second cut in either direction of rotation comprising a ring connected to said cutters for opening and closing them, a pin on the head engageable with openings in the ring for preventing rotation of the ring, and means for rotating said pin about its axis to vary the depth of cut, substantially as set forth.
26. A die head comprising a shank, a body, a ring frame encircling the body said ring frame including a member rigid against rotation independently of said shank, a plurality of cutters, means for adjusting the body about the axis of the head independently of said shank, connections from the cutters to the body and the ring-frame to vary the operative size of the head by such adjustment, and a member fixed to the body said last-named member and said first-named member of the ring frame having on their peripheral faces coacting graduations for indicating the operative size of the head, substantially as set forth.
27. A die head comprising a shank, a body, a ring frame including a member rigid against rotation independently of said shank, a plurality of cutters, means for adjusting the body about the axis of the head independently of the shank, connections from the cutters to the body and the ring-frame to vary the operative size of the head by such adjustment, means for moving the cutters in or out simultaneously to close or open the head, means for locking the head in closed position, means to release the locking means by a forward movement of the head body and connected parts of the ring frame, and a ring fixed to the head body to move axially and rotatably therewith said ring having a flange covering the space between members of the ring frame due to such axial movement and said ring coacting with said first-named member of the ring frame to indicate the operative size of the head by means of graduations on their peripheral faces, substantially as set forth.
28. A die head comprising a shank, a ring frame rigid therewith, a body within the ring frame, cutters carried by said body and connected to said ring frame, means for adjusting said cutters comprising worm teeth on the body, a shaft on the ring frame tangential to the body, a worm on the shaft engaging said teeth, means to prevent end play of the shaft including a head at one end of the shaft bearing against a face on the ring frame there being coacting graduations on the head and the ring frame, a nut at the other end of the shaft bearing against another face on the ring frame, and means to lock said nut against rotation, substantially as set forth.
29. A die head comprising a head body, cutter-holders on the head body, rings about the head body including a closing ring connected to the cutter-holders said ring having recesses at the rear side, a spring for rotating said ring to move the cutter-holders out.

- ward, a shank at the rear of the die head, a plurality of pins holding said shank and head body during operation of said die head in a relatively fixed relation said pins having 5 ends approximately equal in size to the recesses in the closing ring and being movable axially relatively to the head body into and out of engagement with said recesses, substantially as set forth.
- 10 30. A die head comprising a head body, cutters on the head body, rings encircling the head body including an oscillatory ring connected to the cutters, a spring for rotating said ring in a direction to move the cutters 15 outward, a shank at the rear of the head, and a self-locking pin on the shank adapted to engage the closing ring for holding the cutters in working position said pin being wholly withdrawn from said ring to release said 20 ring, substantially as set forth.
31. A die head comprising a shank, a body, a ring frame encircling the body said ring frame including a ring rigid against rotation independently of said shank, a plurality of cutters, means for adjusting the body about its axis independently of said shank including a worm on the ring coacting with teeth on the head body, a head on the worm having graduations coacting with 25 marks on an adjacent part of the die head, connections from the cutters to the head body and the ring frame to vary the operative size of the head by such adjustment, and a member fixed to the head body said last-named 30 member and said first-named ring of the ring frame having on their peripheral faces coacting graduations for indicating the operative size of the head said last-named graduations being adjacent to the head of said worm, substantially as set forth.
32. In a die head, a head body, a supporting shank, chasers on the head body, an oscillatory ring for moving the chasers into and out of operative position, and one or 35 more pins fixed relatively to the shank arranged to engage said oscillatory ring for holding the chasers in operative position said pins being wholly withdrawn from said ring to release the chasers, substantially as set forth. 45
- 50 33. In a die head, a head body, a supporting shank, chasers on the head body, an oscillatory ring for moving the chasers into and out of operative position, and one or more blunt-ended pins fixed relatively to the shank arranged to lock said oscillatory ring positively and directly for holding the chasers in operative position, substantially as set forth. 55
- 60 34. In a cutter head, a head body, elongated chasers on the head body having their major axes lying in lines tangential to the work when in working position, a ring rotatably mounted on the head body for opening and closing the head, and blunt-ended pins 65 adapted to engage the ring for locking the head in closed position one of said pins being adjustable to vary the depth of cut of the chasers, substantially as set forth.
- 70 35. In a die head, a chaser holder, an elongated chaser on the holder having its major axis tangential to the work circle and having serrations on a face parallel to said major axis, a ring encircling the body said ring being connected to said chaser holder to move 75 the chaser into and out of working position, a pin parallel to the axis of the head arranged to engage the ring and to lock it in closed position, and means for rotating the pin about its axis to vary the depth of cut of the chaser, substantially as set forth. 80
- In witness whereof, we have hereunto set our hands at Waynesboro, Pennsylvania, this twenty-ninth day of July, A. D., nineteen hundred and twenty-two.
- SAMUEL F. NEWMAN.
JAMES G. HARPER.
